UNITED STATES PATENT OFFICE.

PATRICK FITZGIBBONS, OF OSWEGO, NEW YORK.

STEAM-BOILER.

SPECIFICATION forming part of Letters Patent No. 274,301, dated March 20, 1883.

Application filed January 16, 1883. (No model.)

To all whom it may concern:

Be it known that I, PATRICK FITZGIBBONS, of Oswego, in the county of Oswego, in the State of New York, have invented new and useful Improvements in Steam-Boilers, of which the following, taken in connection with the accompanying drawings, is a full, clear, and exact description.

This invention consists in the combination, 10 with a return-flue boiler, of a fire-box set with entire length into the end of the boiler, and having a crown-sheet formed with a longitudinal central depression extending the length of the fire-box and joined with the sides of the 15 fire-box by arched side portions of the crown-sheet, and braced by stay-bolts extended from the said arched portions to the upper part of the interior of the boiler, thereby obtaining greater security against the burning of the 20 crown-sheet and a better distribution of the return-flues over the center of the crown-sheet, all as hereinafter more fully explained, and specifically set forth in the claim.

In the annexed drawings, Figure 1 is a longitudinal section of my invention; and Fig. 2 is a vertical transverse section of the same, taken on line *xx*.

Similar letters of reference indicate corresponding parts.

30 B denotes the boiler proper, the same being of the ordinary cylindrical form, placed in a horizontal position.

A represents the fire-box, formed with a water-space, *d*, around its sides and bottom, the outer shell of said water-space being joined to the shell of the boiler, which is cut away at its under side from the rear end forward the distance required to receive through it the fire-box, which is extended into the bottom of the 40 boiler. The crown-sheet *b* of the fire-box I form with a central segmental depression or downward deflection, naturally of a smaller diameter than and concentric with the lower portion of the boiler-shell. Along the two sides 45 of the fire-box the crown-sheet is formed with reverse curved or arched portions *ee*, by which it is joined to the side sheet of the fire-box. The end sheet of the fire-box has its upper edge 50 of a contour corresponding to the central deflection and arched portions of the crown-sheet,

to which said end sheet is joined and riveted in the usual manner.

It will be observed that by the peculiar contour of the crown-sheet *b*, I increase the heating-surface of the fire-box and remove said crown-sheet from the standard water-line of the boiler, and thus more effectually guard against the danger of its becoming uncovered and unprotected by the water and burned by the fire of the fire-box. Furthermore, the central depression of the crown-sheet affords more room for the placement of the return-flues *a a* through the center of the boiler and a better distribution generally of the fire-flues.

In order to properly brace the described 65 crown-sheet *b*, I firmly attach to the top of the arched portions *ee* plates *ff*, to which I connect so-called "crow-foot" stay-bolts *rr*, the upperends of which are securely fastened to the upper portion of the interior of the boiler-shell. 70 That portion of the forward end of the fire-box which is inside of the boiler constitutes a segmental flue-sheet, *c*, to which are connected a series of large direct fire-flues, *CC*, arranged at proper distances apart around the segment 75 formed by the flue-sheet *c*, said direct flues extending longitudinally through the bottom portion of the boiler, and communicating with the usual combustion-chamber, *D*, at the forward end of the boiler.

a a represent the return-flues, extending from the combustion-chamber *D* through the boiler and to the smoke-box *E*, at the opposite end of the boiler, where the products of combustion escape through the stack *S*, mounted 85 on said smoke-box, the greater portion of the return-flues being arranged through the center of the boiler, where the most room is afforded by the deflected crown-sheet, as before described.

Having described my invention, what I claim as new, and desire to secure by Letters Patent, is—

The combination, with the boiler *B*, provided with direct flues *CC* and return-flues *a a*, of 95 the fire-box *A*, set its entire length into the end of the boiler, and having a crown-sheet, *b*, formed with a longitudinal central depression extended the length of the fire-box, and joined with the side sheets by arched side portions *ee* 100

of the crown-sheet, and stay-bolts *rr*, extended from said arched portions to the upper part of the interior of the boiler, the whole constructed and combined substantially in the manner described and shown.

5 In testimony whereof I have hereunto signed my name and affixed my seal, in the presence

of two attesting witnesses, at Syracuse, in the county of Onondaga, in the State of New York, this 1st day of January, 1883.
